UNITED STATES PATENT OFFICE.

JOHN COATES, OF ERIE, PENNSYLVANIA.

WATER-MOTOR.

SPECIFICATION forming part of Letters Patent No. 396,729, dated January 29, 1889.

Application filed November 11, 1887. Serial No. 254,907. (No model.)

To all whom it may concern:

Be it known that I, JOHN COATES, a citizen of the United States, residing at Erie, in the county of Erie and State of Pennsylvania, have invented certain new and useful Improvements in Water-Motors; and I do hereby declare the following to be a full, clear, and exact description of the invention, such as will enable others skilled in the art to which it applies to make and use the same.

This invention relates to water-motors; and it consists in certain improvements in the construction thereof, as will be hereinafter fully described, and pointed out in the claims.

15 My device is illustrated in the accompanying drawings, as follows:

Figure 1 is an elevation perspective view of the cylinder, valve-chamber, and valve-gear. Fig. 2 is a vertical longitudinal section on the line *w w* in Fig. 3, looking in the direction of the arrow on said line. Fig. 3 is a horizontal central section in the line *x x* in Fig. 2. Fig. 4 is a vertical section on the line *y y* in Figs. 1 and 3. Fig. 5 is a vertical section on the line *z z* in Figs. 1 and 3, showing only a fragment of the parts cut by that line.

Letters of reference indicate like parts in each of the figures, as follows:

A is the cylinder; A' A', the passage-chambers; *a a*, the ports of the cylinder; *a' a'*, the passages from the ports to the valve-chamber; D, the valve-chamber; D' D', the valve; *d' d'*, the ports of the valve; *c c*, the exhaust-ports from the valve-chambers; C', the exhaust-nozzle; S, the supply-nozzle.

35 E is a secondary-valve chamber back of the main-valve chamber and at right angles thereto; E' E', the secondary valve; F, the supply-port of said secondary-valve chamber; *f f* and *f' f'*, the ports of said chamber; G, the exhaust-passage from said secondary-valve chamber to the exhaust-passage C' C'.

B is the main piston; B', the main-piston stem; *b*, a tappet-arm on said piston-stem.

45 E² is the stem of the secondary valve E'; *b'* and *e e*, tappets on said stem E²; H, a tappet-lever pivoted on an arm at *h* and connecting with the stem *d* of the main valve.

The construction and operation of my motor are as follows:

The cylinder is of ordinary construction. The passage-chambers A' A' extend from the

opposite ends of the cylinder on opposite sides thereof and meet in circular chambers at the central part of the cylinder, at which point is 55 located the breast A², to which the valve-chamber is attached. The main valve D' stands at right angles to the cylinder. The valve is actuated by the water-pressure, and also by a valve-gear, and as the cylinder A is 60 intended to stand perpendicularly the valve will lie horizontally, which is desirable, as then its weight will not move it when the motor is at rest. This valve is piston form, having two heads, in which are D-passages *d'* on 65 one side, as seen in Fig. 3. The valve-chamber D is provided with entry-ports *d²* *d²* at the ends, which connect with the secondary-valve chamber E, and the supply-port of the secondary-valve chamber is in the opposite 70 wall of the main-valve chamber from the main supply-port S, and is marked F in the drawings. The secondary-valve chamber is set at right angles to the main valve and parallel with the main cylinder. This enables me to 75 move the secondary valve by direct action from the main-piston stem B' by a tappet-arm and tappets. Only one of these tappets, *b'*, is shown, the other being on the rod E² above. On the stem of the secondary valve 80 are placed two other tappets, *e e*, which operate the lever H, which is pivoted at *h* on a fixed arm and has its free end inserted in a slot in the stem *d* of the main valve.

The operation of these valves and gears is 85 as follows: When the piston B is finishing its stroke, one of the tappets *b'* on the valve-rod E² is struck and moved by the tappet-arm *b* on the piston-stem B'. This action moves the secondary valve E', and this admits water to 90 the opposite end of the valve-chamber D through one of the ports *d²*, and it also opens the same port at the opposite end to exhaust, thus changing the pressure of fluid from one end of the valve D' to the other. In case the 95 valve D' did not stick, this change of pressure would move that valve to the opposite end of the valve-chamber; but it cannot be depended upon not to stick. All fluid-actuated valves in water-motors will occasionally stick, 100 and when the motor is used for direct action, as in blowing an organ-bellows, and having no balance-wheel, it is necessary to use a fluid-actuated valve, because there is no elasticity

in the fluid used and no accumulated momentum to carry the valve over the ports. To prevent the valve sticking, I apply a mechanical valve-gear in the form of the lever H and the tappets e e, (or in some other equally-desirable form.) I rig this mechanical gear so that after the secondary valve has commenced its movements the lever H, or such other gear as may be used, is moved, and the valve D' is given a mechanical impetus which will set it in motion, and then the fluid-pressure will complete its movements. As before stated, a mechanical gear cannot be used alone when there is no accumulated momentum, as in a balance-wheel, as it would only move the valve over the ports and then stop, and a pressure-actuated valve is uncertain, because there is often not enough force to start the valve. I therefore combine with a pressure-actuated valve a mechanical gear to give the valve an initial impetus, and thus insure against sticking, and then leave the pressure of the fluid to carry the valve over the ports.

What I claim as new is—

- 25 1. In a water-motor, the combination of a main cylinder, A, having passage-chambers A' A' extending from its ends to its middle point, and then connecting with a breast and an exhaust-passage, a secondary-valve chamber formed within said breast, which is parallel with the cylinder-chamber, and a steam-chest having a main-valve chamber at right angles to said cylinder-chamber fixed on said breast, thereby placing the secondary-valve chamber between the main-valve chamber and the cylinder and at right angles to said main-valve chamber.
- 30 2. In a water-motor, the combination of a main cylinder, A, having passage-chambers A' A' extending from its ends to its middle point, a circumferential exhaust-passage, C', located at said middle point, a breast at said middle point, in which said passages termi-

nate, a valve-chest fixed upon said breast, and having therein a main-valve chamber lying 45 at right angles to the main cylinder and a secondary-valve chamber lying parallel with said cylinder and between said main valve and said cylinder, said valve-chambers containing proper valves and having proper ports and passages, as set forth and shown, a mechanical valve-gear for moving said secondary valve from the main piston, and a mechanical valve-gear for giving the main valve an initial impetus in the direction of the fluid-pressure admitted against it by said secondary valve.

3. In a water-motor, the combination of a main cylinder, A, having passage-chambers A' extending from its end to its middle, a 60 breast, A², at its middle, an exhaust-passage extending from said breast around to an exhaust-nozzle back of said cylinder, a valve-chest attached to said breast containing a main valve which lies at right angles to the 65 cylinder, and a secondary valve which lies parallel with the cylinder, and between it and the main valve, said secondary valve admitting fluid under pressure to the main valve, and the main valve admitting fluid under 70 pressure to the said cylinder, substantially as set forth.

4. In a water-motor, the combination of a main-piston chamber, a main-valve chamber at right angles to said piston-chamber, a secondary valve between the main-valve and the piston chamber, which is at right angles to the main valve, and a lever for communicating motion from said secondary-valve stem to the stem of said main valve.

In testimony whereof I affix my signature in presence of two witnesses.

JOHN COATES.
